WORK-HOLDER FOR DARNING, MENDING,
EMBROIDERING, ETC.

Clara K. Fincke, Kansas City, Kans.

Application May 31, 1930. Serial No. 457,922

8 Claims. (Cl. 45—24)

This invention has reference to work-holders of the class designed for mending, darning and embroidery work and the like, and aims to provide an improved device of this character which 5 will enable the work to be held in the most effective position for carrying out the desired operation.

One special object of my invention is to devise a holder construction whereby the work 10 may be conveniently applied to the holder and securely held thereby in a tightly stretched condition across one face of the holder frame by retaining means forming part of said face of the frame but interfering in no way with the application and stretching of the goods.

It is also sought to provide an improved holder construction in which the means employed for clamping the work in position upon the holder frame not only cooperates with the retaining elements formed as a part of one face of the holder frame, but is retained securely in proper position by said elements and thus prevented from being crowded out of operative position by any pushing or pulling action of the goods on account of their being stretched or distended upon the frame.

With these various general objects in view the invention will now be further described in more detail by reference to the accompanying drawing 30 illustrating a practical and efficient embodiment of the various features of improvement, after which the novel points and combinations of the same will be particularly set forth in the appended claims.

35 In the drawing—

Figure 1 is a plan view, showing a work-holder embodying the present improvements;

Figure 2 is a similar view illustrating the mode of use of the device;

40 Figure 3 is a section on line 3—3 of Figure 2; and

Figure 4 is a fragmentary detail view, showing a portion of the device.

Referring now to the drawing in detail, the 45 same illustrates the improved holder construction as comprising a holder frame 5 which may be of any desired size and preferably of oval or elliptical form, and also having an exterior groove or channel 6 for cooperation with an endless coil spring 7 which functions as a clamping band adapted to seat in the channel 6 and thereby secure the goods, such as a stocking or hose 8, to the frame 5 with that portion of the material which is to be darned or mended stretched across 50 the opening within the frame, as shown in Figure 2.

At one side of the groove or channel 6, the holder frame is provided with a series of work-holding fingers 10 which may be formed of any suitable 55 material of the desired stiffness or rigidity, such

as sheet metal, secured to or integral with the frame 5. These fingers are of angular form, extending in a generally upward and outwardly flaring relation from the holder frame, the lower portions of the fingers projecting in approximately vertical position, while the outer ends of the fingers are of somewhat wavy contour as shown. These lower portions are also stamped out to provide outwardly and upwardly projecting hook or detent elements 12.

The construction thus far described is in general similar to that set forth in my copending application Serial Number 450,750, filed May 8, 1930, the function of the fingers 10 being to provide suitable abutments against which the main portion of the work comprising the article 70 is crowded or bunched, when the device is inserted within a hose, with that portion to be mended properly stretched across the opening within the frame, as shown in Figure 2. The upwardly extending portions of the fingers 10 are relatively short, since one object aimed at in the device is to maintain as shallow or squat a condition of the work as possible, and this also enables the holder and the work after it has been mounted thereon to be readily inserted within the working parts of a sewing machine, if desired.

Since the crowding of the work into the position between the groove or channel 6 and the terminal portions of the fingers 10 would have a tendency to crowd the clamping spring 7 out of the groove or channel 6, the series of so-called detent elements 12 is provided, as in my copending application, which function not only as abutments cooperating with the upwardly projecting portions of the fingers 10, but as detent elements for holding the work up away from the groove or channel 6, and preventing it from working further down upon the frame 5 and thereby tending 80 to crowd the spring out of its groove.

As a further aid in securing a properly stretched condition of the work across the opening within the holder frame, as well as in aiding to retain the clamping spring 7 in seated position, I have 85 devised an additional series of hooks or detent elements 16 which I form as a part of the opposite or lower margin of the groove or channel portion 6 of the frame 5. These elements are of curved hook form, the curve being approximately 90 a continuation of the curvature of the groove or channel 6, thus forming an additional rest or extension of the seat for the spring; the elements 16 are preferably arranged in pairs, one pair for each space corresponding to the space between 95 two adjoining pairs of fingers 10, as shown in Figure 1.

The holder is inserted into the work, or the work applied to the holder, in the regular way, and the goods pulled back over the hooks 16 and 100

channel 6, into the position illustrated in Figure 2. The curvature of the hook elements 16 permits the goods to be stretched smoothly across the outer faces of the hooks, one such stretching operation taking place as the spring 7 is snapped into the channel 6; thereafter the goods may be tensioned still further, if desired, to stretch the material, by pulling on the goods above the spring band, the curvature of the hooks facilitating the pulling and drawing of the goods around them.

But any opposite movement of the material is positively prevented by the clamping action of the band 7 after it is seated within the channel 6 and against the concave faces of the hook elements 16 as represented in Figure 2.

It will be apparent that the provision of the improved features of construction provides a holding means for the goods substantially flush with the face of the holder frame across which the material is to be stretched for the sewing or mending operation, and the material is securely held by being firmly clamped between said hooks and the spring 7, due to the latter seating against the concave faces of the hook. A much more positive holding function is thus exerted than could be secured by the mere use of the spring 7 and the channel 6, without such hook elements, and with certain kinds of work it is very essential that the tautly stretched condition of the work be maintained as tense as the character of the goods will permit, throughout the use of the device.

I have therefore devised an improved construction possessing all the advantages of that forming the subject matter of my aforesaid application, but with distinct additional advantages of a very useful character, and while I have illustrated and described what I now regard as the preferred form of construction for embodying said improvements, I desire to reserve the right to make such changes or modifications as may fairly fall within the scope of the appended claims.

What I claim is:

45 1. A work-holder for darning or mending operations, comprising a frame providing an open space surrounded by a peripheral channel, and an endless resilient clamping band adapted to seat in said channel, and a plurality of detent elements surrounding said channel and forming outward continuations of the edge thereof which defines said open space, said elements having concave faces for cooperating with said band to clamp the work across said open space and smooth convex exterior faces contacting with the work for permitting the sliding of the goods as the material is tensioned for stretching the same while preventing peripheral shifting movement of the work about said open space.

50 2. A work-holder for darning or mending operations, comprising a frame providing an open space surrounded by a peripheral channel, a spring clamping member seating in said channel for holding the work in stretched condition across said open space, a plurality of work-engaging elements projecting from one side of said channel for accommodating the unstretched portion of the work out of engagement with the clamping member, and a series of hook-shaped detent elements projecting outward from the opposite side of said channel in position for cooperating with the clamping member in stretching the work across the open space, said detent elements having smooth convex exterior faces permitting free

outward sliding of the goods in response to the pull of the clamping member while preventing peripheral shifting of the work about said open space.

55 3. A work-holder for darning or mending, comprising an open frame, relatively slender finger members rigidly connected with the frame and projecting away from the same at approximately right angles to the plane of the frame and each terminating in a work-retaining hook portion, and an exterior work-engaging hook element rigid with the base portion of each of said finger members, whereby each finger member is formed with a pair of cooperative hook portions for retaining the work therebetween in bunched relation.

60 4. A work-holder for darning or mending, comprising an open frame having means for clamping the work to the exterior thereof, a plurality of work-retaining fingers rigidly connected with the frame and projecting laterally outward with reference to the plane of the frame, said fingers as a group also projecting in diverging relation away from the frame in position to distend the engaged portion of the work to an extent greater than the size of said frame, and a work-engaging hook element rigid with the exterior of each of said fingers adjacent to its connection with the frame and projecting angularly and outwardly away from the frame.

65 5. A work-holder for darning or mending, comprising an open frame provided with work-holding elements projecting therefrom and rigidly connected with the frame, means for clamping the work to the periphery of said frame, and work-holding means rigid with said frame and providing exterior hook-shape shoulders directly adjacent to said frame for engagement with the work and positively preventing the work from crowding said clamping means off the frame.

70 6. A work-holder for darning or mending, comprising an open frame, means for clamping the work to the periphery of the frame, work-retaining means for accommodating the work in distended condition above the frame, and outwardly projecting detent elements rigid with said frame and extending between said clamping means and said work-retaining means for preventing the work from crowding the clamping means off the frame.

75 7. A work-holder for darning or mending, comprising an open frame, retaining members extending upwardly and outwardly from the frame for accommodating the work in distended condition above the frame, clamping means for clamping the work against the frame, and means forming a part of said frame and projecting upwardly and outwardly between said clamping means and retaining members for cooperating with the latter in holding the work in bunched relation and for preventing the work from crowding the clamping means out of operative position.

80 8. A work-holder for darning or mending, comprising an open frame formed with an exterior annular groove, an annular spring member seating in said groove for clamping the work to said frame, and a series of relatively rigid work-holding fingers carried by said frame for retaining the work in distended condition above the frame said frame being provided with a plurality of detent elements projecting upwardly and outwardly from the upper margin of said groove for engagement with the work and preventing the same from crowding the spring member off the frame.
